A gaming device including a rotatable mechanical award indicator which has a plurality of award symbols. The gaming device includes a mask, preferably overlaying the mechanical award indicator, which reveals only a predetermined number of the award symbols. In one embodiment, the gaming device includes a plurality of player selectable symbols associated with different movements of the mechanical award indicator. This type of gaming device adds excitement to bonus games and increases player entertainment.

**GAMING DEVICE HAVING A ROTATABLE
MECHANICAL AWARD INDICATOR
PARTIALLY COVERED BY A MASK**

PRIORITY CLAIM

This application is a non-provisional of, claims priority to and the benefit of U.S. Provisional Application Ser. No. 60/490,879, filed Jul. 29, 2003, the entire contents of which are incorporated herein.

CROSS REFERENCE TO RELATED
APPLICATIONS

This application relates to the following co-pending, commonly owned application: "GAMING DEVICE HAVING A DISPLAY DEVICE HAVING MULTIPLE ROTATABLE MEMBERS," Ser. No. 11/470,167.

COPYRIGHT NOTICE

A portion of the disclosure of this patent document contains or may contain material which is subject to copyright protection. The copyright owner has no objection to the photocopy reproduction by anyone of the patent document or the patent disclosure in exactly the form it appears in the Patent and Trademark Office patent file or records, but otherwise reserves all copyright rights whatsoever.

BACKGROUND OF THE INVENTION

The present invention relates in general to a gaming device, and more particularly to a wagering gaming device having a rotatable mechanical award indicator partially covered by a mask.

Certain gaming machines include a primary or base game and a secondary or bonus game. A common primary game such as a slot game includes rotatable reels. Typically, a bonus game begins when a predetermined symbol or symbol combination is generated on the reels. The bonus game provides the player with an opportunity to gain one or more bonus values or awards.

One known bonus game involves a mechanical wheel. The wheel is attached to the top of the gaming device cabinet and is divided into several pie-shaped sections. Each section includes an award which ranges in value from twenty-five to one thousand. All of the award values are visible to the player at all times. When the bonus game is triggered, the player causes the wheel to spin by pressing a play button. When the wheel stops spinning, an indicator points to a section of the wheel. The player receives the award displayed on that section.

In this bonus game, the player cannot affect the direction in which the wheel spins, nor can the player affect to what extent the wheel rotates before stopping. Furthermore, this bonus game does not include a mask which masks one or more of the sections or values. To increase player enjoyment and excitement, it is desirable to provide players with new wagering gaming devices including new games such as primary and secondary games.

SUMMARY OF THE INVENTION

The gaming device of the present invention, in one embodiment, includes: (a) a rotatable mechanical award indicator such as a mechanical wheel or reel, which includes a plurality of awards symbols such as bonus values; (b) a

2

suitable actuator or motor which drives the mechanical award indicator; and (c) a panel or mask which preferably partially overlays the mechanical award indicator.

The mask includes any suitable cover or surface which allows a player to view one or more (but not all) of the award symbols. In one embodiment, the mask includes a panel which defines an opening or window positioned adjacent to the mechanical award indicator. The mask is opaque in one embodiment and the window can include a fully or partially transparent surface, a fully or partially translucent surface, an opening, a slot or hole or a series of openings, slots or holes. In one embodiment, the window includes a transparent plastic window constructed within the body of the mask.

In one embodiment, the award symbols are fixed. In other embodiments, the award symbols may change, such as in each iteration of the play of the game. In an alternative embodiment, the award indicator is a video display which is operable to display the award symbols.

In one embodiment, the game includes a plurality of selections or selection symbols. Each of the selection symbols is preferably associated with: (a) one or more move indicators; (b) one or more probabilities; and (c) one or more move specifications. The move specifications may be fixed or predetermined, or randomly determined. When the player selects one of the selection symbols, the actuator or motor drives the mechanical award indicator to a position. The particular position at which the mechanical award indicator stops, depends on which selection symbol the player chooses.

When the mechanical award indicator stops rotating, the window reveals one award symbol. The gaming device can provide the player with an award associated with this award symbol. This can be repeated a designated number of times for each of a designated number of picks of selections by the player. In an alternative embodiment, the gaming device can provide the player with an opportunity to accept or reject an award associated with this award symbol for each of a designated number of picks of the selections. If the player accepts an award, the game ends.

In one alternative embodiment, the gaming device does not include any selection symbols. Instead, when a predetermined game event occurs, or when the player makes a predetermined input, the mechanical award indicator rotates and stops, and the window reveals a set of award symbols to the player. The gaming device enables the player to accept or reject this set. Once the player accepts a set, the gaming device indicates one of the awards symbols in that set to the player. The gaming device then provides the player with an award associated with the indicated award symbol.

In one embodiment, the gaming device of the present invention includes a mechanical award indicator which includes a rotatable mechanical object such as a reel having a plurality of award symbols. A cover and window combination or a mask overlays the rotatable object, thereby masking a predetermined number of award symbols from the player's view. In one embodiment, the mechanical award indicator provides the player with the opportunity to gain award values displayed on the rotatable mechanical object. When a particular event occurs, the gaming device rotates the mechanical reel, reveals a value to the player and awards that value to the player. In another embodiment, the gaming device provides the player with a predetermined number of opportunities to accept or reject award values revealed to the player. Various alternative methods for providing players awards are contemplated by the present invention.

It is therefore an advantage of the present invention to provide a gaming device having a rotatable mechanical award indicator at least partially covered by a mask.

Another advantage of the present invention is to provide a gaming device having a primary game or bonus game which involves a mechanical wheel or reel at least partially covered by a mask which reveals certain award values to players.

Another advantage of the present invention is to provide a gaming device including a mechanical award indicator whose direction of movement and/or magnitude of movement can be affected by the player.

Other objects, features and advantages of the invention will be apparent from the following detailed disclosure, taken in conjunction with the accompanying sheets of drawings, wherein like numerals refer to like parts, elements, components, steps and processes.

BRIEF DESCRIPTION OF THE DRAWINGS

FIG. 1 is a perspective view of one embodiment of the gaming device of the present invention illustrating a vertically mounted mechanical reel and one player visible bonus value on the reel.

FIG. 2 is a perspective view of the gaming device shown in FIG. 1 illustrating a plurality of selection symbols in a bonus game and a vertically mounted mechanical reel revealing one bonus value.

FIG. 3 is a table illustrating a plurality of selection symbols and a plurality of move indicators, probabilities and move specifications associated with the selection symbols.

FIG. 4 is a perspective view of one embodiment of the gaming device of the present invention illustrating a plurality of selection symbols in a primary game and a horizontally mounted mechanical reel revealing one value.

FIG. 5 is a perspective view of one embodiment of the gaming device of the present invention illustrating a plurality of reels in a primary game, a plurality of selection symbols in a bonus game and a top mounted mechanical wheel revealing one bonus value.

FIG. 6 is a perspective view of one embodiment of the gaming device of the present invention illustrating a plurality of reels in a primary game, a mechanical reel revealing one of a plurality of sets of values and an award indicator.

FIG. 7 is a schematic view of the electronic configuration of the gaming device in one embodiment of the present invention.

DETAILED DESCRIPTION OF THE INVENTION

Gaming Device Structure and Electronic Configuration

Referring now to FIGS. 1 to 7, gaming devices 10a, 10b, 10c and 10d include the mechanical award indicators 112a, 112b, 112c or 112d, respectively, as described below. In one embodiment, gaming devices 10a to 10d, generally referred to as gaming device 10, is a slot machine having the controls, displays and features of a conventional slot machine. It is constructed so that a player can operate it while standing or sitting. It should be appreciated that gaming device 10 can be constructed as a pub-style table-top game (not shown) which a player can operate preferably while sitting. Furthermore, gaming device 10 can be constructed with varying cabinet 11 and display designs, as illustrated by the designs shown in FIGS. 1, 2 and 4 to 6.

Gaming device 10 can incorporate any suitable primary game such as slot, poker or keno, any of their suitable bonus triggering events and any of their suitable bonus round games. The symbols and indicia used on and in gaming device 10 may be in mechanical, electrical or video form.

As illustrated in FIGS. 1, 2 and 4 to 6, gaming device 10 includes a coin slot 12 and bill acceptor 14 where the player inserts money, coins or tokens. The player can place coins in the coin slot 12 or paper money or ticket vouchers in the bill acceptor 14. Other devices could be used for accepting payment such as readers or validators for credit cards or debit cards. When a player inserts money in gaming device 10, a number of credits corresponding to the amount deposited is shown in a credit display 16. After depositing the appropriate amount of money, a player can begin the game by pulling arm 18 or pushing play button 20. Play button 20 can be any play activator used by the player which starts any game or sequence of events in the gaming device.

Gaming device 10 also includes a bet display 22 and a bet one button 24. The player places a bet by pushing the bet one button 24. The player can increase the bet by one credit each time the player pushes the bet one button 24. When the player pushes the bet one button 24, the number of credits shown in the credit display 16 decreases by one, and the number of credits shown in the bet display 22 increases by one.

A player may cash out and thereby receive a number of coins corresponding to the number of remaining credits by pushing a cash out button 26. When the player cashes out, the player receives the coins in a coin payout tray 28. The gaming device 10 may employ other payout mechanisms such as credit slips redeemable by a cashier or electronically recordable cards which keep track of the player's credits.

Gaming device 10 also includes one or more display devices. The embodiment shown in FIGS. 1, 2 and 4 includes a central display device 30, and the alternative embodiment shown in FIG. 5 includes a central display device 30 as well as an upper display device 32. Gaming device 10 may display a plurality of reels 34, such as three to five reels 34 in mechanical or video form at one or more of the display devices. A display device can be any viewing surface such as glass, a video monitor or screen, a liquid crystal display or any other display mechanism.

If the reels 34 are in video form, the display device for the video reels 34 is preferably a video monitor. Each reel 34 displays a plurality of indicia such as bells, hearts, fruits, numbers, letters, bars or other images which preferably correspond to a theme associated with the gaming device 10. Furthermore, gaming device 10 preferably includes speakers 36 for making sounds or playing music.

As illustrated in FIG. 7, the general electronic configuration of gaming device 10 preferably includes: a processor 38; a memory device 40 for storing program code or other data; one or more motors 116a, 116b or 116d; a central display device 30; an upper display device 32; a sound card 42; a plurality of speakers 36; and one or more input devices 44. The processor 38 is preferably a microprocessor or microcontroller-based platform which is capable of displaying images, symbols and other indicia such as images of people, characters, places, things and faces of cards.

Preferably, the memory device 40 stores the random generator program described below as well as the values and associated probabilities and move specifications described below. The memory device 40 can include random access memory (RAM) 46 for storing event data or other data generated or used during a particular game. The memory device 40 can also include read only memory (ROM) 48 for

storing program code which controls the gaming device 10 so that it plays a particular game in accordance with applicable game rules and pay tables.

The player preferably uses the input devices 44, such as pull arm 18, play button 20, the bet one button 24 and the cash out button 26 to input signals into gaming device 10. In certain instances it is preferable to use a touch screen 50 and an associated touch screen controller 52 instead of a conventional video monitor display device. Touch screen 50 and touch screen controller 52 are connected to a video controller 54 and processor 38. A player can make decisions and input signals into the gaming device 10 by touching touch screen 50 at the appropriate places. As further illustrated in FIG. 7, the processor 38 can be connected to coin slot 12 or bill acceptor 14. The processor 38 can be programmed to require a player to deposit a certain amount of money in order to start the game.

It should be appreciated that although a processor 38 and memory device 40 are preferable implementations of the present invention, the present invention can also be implemented using one or more application-specific integrated circuits (ASIC's) or other hard-wired devices, or using mechanical devices (collectively or alternatively referred to herein as a "processor"). Furthermore, although the processor 38 and memory device 40 preferably reside on each gaming device 10 unit, it is possible to provide some or all of their functions at a central location such as a data network 41 or network server for communication to a playing station such as over a local area network (LAN), wide area network (WAN), Internet connection, microwave link, and the like. In addition, the gaming device processor 38 can communicate with a server over a data network 41. For example, the processor 38 can exchange game data with a gaming facility server by communicating with such server over a gaming facility network. The processor 38 and memory device 40 is generally referred to herein as the computer or controller.

To generally operate the gaming device 10 in one embodiment the player must insert the appropriate amount of money or tokens at coin slot 12 or bill acceptor 14 and then pull the arm 18 or push the play button 20. The reels 34 will then begin to spin. Eventually, the reels 34 will come to a stop. As long as the player has credits remaining, the player can spin the reels 34 again. Depending upon where the reels 34 stop, the player may or may not win additional credits.

In addition to winning credits in this manner, preferably gaming device 10 also gives players the opportunity to win credits in a bonus round, as illustrated in FIGS. 1 to 6. This type of gaming device 10 will include a program which will automatically begin a bonus round when the player has achieved a qualifying condition in the game. This qualifying condition can be a particular arrangement of indicia on a display device. The gaming device 10 preferably uses one of the award indicators 112a, 112c or 112d to play the bonus round. Preferably, the qualifying condition is a predetermined combination of indicia appearing on a plurality of reels 34. As illustrated in the five reel slot game shown in FIGS. 1, 5 and 6, the qualifying condition could be the number seven appearing on three adjacent reels 34 along a payline 56. It should be appreciated that the present invention can include one or more paylines, such as payline 56, wherein the paylines can be horizontal, diagonal or any combination thereof.

Mechanical Award Indicator

In one embodiment illustrated in FIGS. 1 to 3, the mechanical award indicator 112a includes: (a) a mechanical

reel 114a which is coupled to and driven by an actuator such as a motor 116a; and (b) a panel or mask 118a which preferably overlays the mechanical reel 114a. The mechanical reel 114a includes a plurality of award symbols such as bonus values 120a. The bonus values 120a are preferably affixed to the mechanical reel 114a in a mechanical fashion, such as in the form of paint or decals. It should be appreciated, however, that the bonus values 120a can additionally or alternatively be formed with one or more suitable electrical light sources.

In one embodiment, the mask 118a includes any suitable cover or surface which enables a player to only view one of the bonus values and in another embodiment to view more than one (but not all) of the bonus values 120a which would otherwise be visible to the player. In one embodiment, the mask 118a includes a panel which generally covers the upper portion of the gaming device 10a. Here, the mask 118a defines a window 122a positioned adjacent to the mechanical reel 114a. The position of one of the values 120a facing the front of the gaming device 10a can be aligned with the position of the window 122a. In the example shown in FIGS. 1 and 2, the bonus value 124a has a position aligned with the position of the window 122a. Accordingly, although the mechanical reel 114a bears a plurality of bonus values 120a, in the illustrated embodiment the player can only view the bonus value 124a.

When a player reaches a predetermined event or bonus triggering event while playing the primary game, the bonus game begins. In one embodiment, the bonus game includes a plurality of selection symbols 126a to 126f. Each of the selection symbols 126a to 126f is preferably associated with: (a) one or more move indicators 128; (b) one or more probabilities 130; and (c) one or more move specifications 132, as illustrated in FIG. 3.

The move indicators 128, which can include any suitable symbols, preferably inform the player about the move specifications 132 associated with the selection symbols 126a to 126f. The probabilities 130 include the mathematical probability that the player will reach a particular move specification 132 by selecting a particular selection symbol 126a to 126f. Accordingly, one or more, and preferably each of the bonus values 120a is associated with: (a) a selection symbol 126a to 126f; (b) one or more move indicators 128; (c) one or more probabilities 130; and (d) one or more move specifications 132. In one embodiment, the average expected value to be gained by the player can thus be determined for each of the selection symbols 126a to 126f by using a suitable calculation based upon such probabilities and the award values.

The player can select one or more of the selection symbols 126a to 126f by activating a suitable input device. Preferably, when the player presses a predetermined input button 120, the motor 116a drives the mechanical reel 114a causing the reel to make a predetermined rotation. The rotation begins at a predetermined start position and ends at a predetermined stop position. When the reel 114a stops rotating at the stop position, a bonus value 120a is displayed through the window 122a. The gaming device can automatically award the player with the displayed bonus value 124a, or in an alternative embodiment enable the player to accept or reject this value. If the player rejects this value, the player may choose another selection symbol 126a to 126f. In one embodiment, if the player accepts this value, the player can still choose another selection symbol 126a to 126f. This process can repeat itself a predetermined number of times. In another embodiment, if the player accepts a displayed value, the bonus game terminates. The number of picks of

the selections can be determined in any suitable manner. It should thus be appreciated that the player may obtain one award or a plurality of awards.

Regardless of the particular embodiment, the bonus game continues until the player reaches a termination condition. A termination condition can occur when the mechanical reel 114a has made a predetermined number of rotations, when a player has accepted or been awarded with a predetermined amount of values, when a player has rejected a predetermined number of bonus values, when the mechanical reel 114a stops and the window 122a displays a termination symbol, or when any other predetermined event occurs. Once the bonus game terminates, the gaming device awards the player with the values the player has gained.

In another embodiment, the bonus game includes a set or pool of different selection symbols, and each selection symbol is associated with a different move specification. Upon the initiation of each bonus game, the gaming device processor randomly generates or selects a predetermined number of the selection symbols from this pool. For example, the pool may include one hundred different selection symbols. The gaming device processor may use a suitable random number generator program to randomly select five of these selection symbols. The gaming device then displays these selection symbols, enables the player to select one or more of the displayed selection symbols and rotates the mechanical wheel in accordance with the move specifications associated with the selection symbols selected by the player.

In another embodiment, the bonus game includes a predetermined number of selection symbols. These same selection symbols, each associated with a move specification, are displayed on the display device for each game. The bonus values on the mechanical reel or wheel are formed through one or more electrical light sources. When the player selects a selection symbol, the gaming device uses a random number generator program to produce a bonus value for a particular position on the mechanical reel or wheel. The gaming device then causes the light source at that position to form such value. This prevents the player from controlling the payout by memorizing the moves associated with the selection symbols.

In another embodiment illustrated in FIG. 4, the gaming device 10b includes the mechanical award indicator 112b. Mechanical award indicator 112b includes: (a) a mechanical reel 114b coupled to and driven by the motor 116b; and (b) a panel or mask 118b which preferably overlays the mechanical reel 114b. The mechanical reel 114b is mounted horizontally within cabinet 11. From this illustration, it should be appreciated that the rotatable mechanical object of the present invention can be mounted in various positions, including, without limitation, in the cabinet 11 or as part of a topper on top of the cabinet 11 in vertical, horizontal, diagonal or other positions or orientations.

In this embodiment, the primary game includes a plurality of selection symbols 138a to 138f. During the primary game, the gaming device processor enables the player to select one or more of the selection symbols 138a to 138f. Each of the selection symbols 138a to 138f is associated with a move specification. When the player selects one of the selection symbols 138a to 138f, the gaming device processor causes the motor 116b to move the mechanical reel 114b in accordance with the move specification associated with such selection symbol.

It should be appreciated that the move specifications can be fixed, predetermined, randomly determined, determined from a table or otherwise suitably determined. Thus, each

time a player selects a selection symbol, the move specification associated with that selection symbol may be the same or may be different. This adds fun and excitement to the game, because the player does not know how many positions the reel will move and also cannot see the upcoming values of the positions. This combination of unknowns is fun and exciting for the player.

As further illustrated in FIG. 4, the symbols 120b can include symbols other than values. In this example, symbol 125 is a "T" which represents termination. If mechanical reel 114b stops with symbol 125 displayed at the window 122b, the primary game automatically terminates. It should be appreciated that the mechanical award indicator in the gaming device of the present invention can include any suitable type of symbol which, when reached by a player, causes the gaming device to perform any predetermined event. For example, certain symbols, when reached by a player, may result in a predetermined movement of the mechanical reel or wheel, a predetermined bonus award or value, a predetermined opportunity to gain a bonus award or value, or a predetermined penalty, such as the loss of available inputs, value or credits.

In one embodiment illustrated in FIG. 5, gaming device 10c includes an award indicator 112c mounted on the top portion of the cabinet 11. The award indicator 112c includes: (a) a mechanical wheel 114c coupled to and driven by a motor (not shown); and (b) a panel or mask 118c which preferably overlays the mechanical wheel 114c. The mechanical wheel 114c is preferably orientated such that the axis of mechanical wheel 114c extends into the gaming device 10c. The mechanical wheel 114c includes a plurality of bonus symbols 120c. Bonus symbols 120c are preferably bonus values. The mask 118c covers mechanical wheel 114c and includes a window 122c, preferably transparent or translucent, which enables the player to view the symbol 124c which is located behind that window 122c.

In operation, while playing the primary game, a player reaches a bonus triggering event displayed at the display device 30. The display device 32 then displays a plurality of selection symbols 142a to 142f. A move specification is associated with each of the selection symbols 142a to 142f. The player may then push a button 120 to select one of the selection symbols 142a to 142f. The gaming device processor causes the motor to rotate the mechanical wheel 114c in accordance with the move specification associated with the selected selection symbol 142a to 142f. During rotation, the player only sees one of the bonus values 120c at a time, as each value passes under window 122c. In one embodiment, the gaming device 10c stops the wheel 114c at a predetermined stop location and displays a value 124c through the window 122c. In one embodiment, the player gets such value. In another embodiment, the gaming device 10c gives the player the option of accepting this value or rotating the wheel 114c for another value. This process repeats itself a predetermined number of times or until a predetermined event occurs. When the player finally accepts or otherwise receives one or more values, the gaming device enables the player to play the primary game again, or the gaming device provides the player with the gained values and then terminates the bonus game.

In another embodiment illustrated in FIG. 6, the gaming device 10d includes the mechanical award indicator 112d. The mechanical award indicator 112d includes: (a) a mechanical reel 114d which is coupled to and driven by a motor 116d; (b) a cover or mask 118d which displays select portions of the mechanical reel 114d; and (c) an indicator 144 which indicates certain symbols 120d on the mechanical

reel 114d. A plurality of symbols 120d (preferably bonus values) are affixed to or otherwise displayed on the mechanical reel 114d. The mask 118d is connected to the cabinet 111 of the gaming device 10d. The mask 118d covers the mechanical award indicator 112d and includes a window 122d which is preferably transparent. The mask 118d enables the player to view a set 146 of symbols 120d at one time. In the example shown in FIG. 6, window 122d enables the player to view three bonus values (forty, twenty-five and three-hundred) at one time. In an example not illustrated in FIG. 6, the mask 118d includes separate windows, one for each displayed symbol.

Indicator 144 indicates predetermined bonus values 120d in the set 146 to the player. Preferably, indicator 144 includes a plurality of light sources or lamps 148a, 148b and 148c extending through the mask 118d. Each lamp is preferably mounted adjacent to one of the bonus symbols 120a displayed through the window 122d. In the example illustrated in FIG. 6, the lamps 148a to 148c have an arrow shape. In this example, the gaming device is indicating to the player, the bonus value 120d in the amount of three hundred by illuminating lamp 148c. It should be appreciated that the gaming device can include any suitable indicator or device which is suitable for identifying to a player one or more bonus symbols 120d. Suitable indicators can be affixed to or displayed on the mask 118d or reel 114d. Such indicators can include electrical lighting, sound effects or predetermined sound recordings, or video-based imaging which interfaces with the mechanical reel 114d.

In operation of gaming device 10d, when the player reaches a predetermined event during a primary game, the bonus game begins. The player may cause the mechanical reel 112d to rotate by making a predetermined input. Alternatively, the gaming device processor may automatically cause the mechanical reel 112d to rotate. In either case, when the mechanical reel 112d stops rotating, the gaming device displays a pool or set 146 of bonus symbols 120d to the player through window 122d. It is preferable that the bonus symbols 120d are bonus values.

In one embodiment, the gaming device 10d automatically indicates one of the bonus values 120d in the set 146 and awards this bonus value to the player. In another embodiment, prior to indicating one of the bonus values 120d in the set 146, the gaming device enables the player to accept or reject this predetermined set 146. If the player rejects this set 146 of bonus values 120d, the mechanical reel 120d rotates again, stops and displays another set 146 of bonus values 120d to the player. The player may accept or reject this set of bonus values 120d. This process may repeat itself a predetermined number of times. If the player accepts a particular set 146 of bonus values, the gaming device automatically indicates one of the bonus values within that set and awards that bonus value to the player. When a termination event occurs, such as the player accepting or rejecting a predetermined number of sets, the bonus game terminates. Upon termination of the bonus game, the gaming device awards the player with any bonus values the player has accumulated.

In one alternative embodiment of the present invention, the gaming device enables the player to control the number of symbols which pass through the window before the mechanical reel stops rotating. For example, the player can use the input button to make a desired or predetermined move specification. A move specification can specify the magnitude of rotational movement for the reel and/or the rotational direction of the reel. Preferably, in this embodiment the symbols or values on the reel are displayed through

electrical lighting which the gaming device controls. This prevents players from memorizing symbol locations and controlling their payout by controlling the reel movement. It is thus preferable that the gaming device changes the values following each rotation made by a player.

In the embodiments illustrated above, the mechanical award indicator includes a mechanical reel. It should be appreciated, however, that the mechanical award indicator can include various rotatable mechanical objects other than a wheel or reel, including without limitation, objects of hexagonal, cubic, spherical, triangular, oval, square, star and other suitable polygonal shapes.

The gaming device 10 can be manufactured in any suitable manner. The actuators or motors 116a, 116b and 116d are generally referred to as motor 116; rotatable mechanical objects 114a, 114b, 114c and 114d are generally referred to as rotatable mechanical object 114; masks 118a, 118b, 118c and 118d are generally referred to as mask 118; award symbols 120a, 120b, 120c, and 120d are generally referred to as award symbols 120; and windows 122a, 122b, 122c and 122d are generally referred to as window 122. In one embodiment, gaming device 10 can be manufactured by: (a) assembling the gaming device cabinet 11; (b) connecting at least one suitable motor support member (not shown) to the gaming device cabinet 11; (c) connecting a motor 116 to the motor support member; (d) coupling a rotatable mechanical object 114 to the motor 116, wherein the rotatable mechanical object 114 has a plurality of award symbols 120; (e) connecting a mask 118 to the cabinet 11 over at least part of the rotatable mechanical object 114 so that the mask 118 defines at least one window 122; (f) connecting at least one suitable display device support member to the cabinet; (g) connecting at least one display device 130 or 132 to the display device support member; (h) electrically or electronically connecting at least one processor 138 to the display device 130 or 132; and (i) electrically or electronically connecting at least one memory device 140 to the processor 138.

In order to manufacture the embodiments illustrated in FIGS. 1 to 5, one must also: (a) store selection symbol data in the memory device 40 wherein the selection symbol data represents a plurality of graphical selection symbols; (b) store move specifications in the memory device 40, wherein each of the move specifications is associated with one of the graphical selection symbols; (c) connect at least one suitable input device support member (not shown) to the cabinet 11; and (d) connect at least one input device, such as input device 20, to the input device support member which enables the player to select the selection symbols.

The gaming device of the present invention, in one embodiment, includes a rotatable mechanical award indicator covered by a mask. The mask reveals a limited number of award symbols on the mechanical award indicator. In one embodiment, the gaming device enables the player to accept or reject certain award symbols or award symbols sets revealed by the mask. In another embodiment, the gaming device enables the player to affect to what extent or in what direction the mechanical award indicator rotates by selecting one of a plurality of selection symbols. This type of gaming device increases the excitement and entertainment experienced by gaming device players.

While the present invention has been described in connection with what is presently considered to be the most practical and preferred embodiments, it is to be understood that the invention is not limited to the disclosed embodiments, but on the contrary is intended to cover various modifications and equivalent arrangements included within

11

the spirit and scope of the claims. It is thus to be understood that modifications and variations in the present invention may be made without departing from the novel aspects of this invention as defined in the claims, and that this application is to be limited only by the scope of the claims.

The invention claimed is:

1. A gaming device comprising:

a cabinet;

at least one actuator supported by the cabinet;

a rotatable mechanical object operatively coupled to the actuator, the rotatable mechanical object having a plurality of award symbols, each award symbol associated with a different stop position on the rotatable mechanical object;

a mask connected to the cabinet, the mask covering at least part of the rotatable mechanical object and defining at least one window;

a plurality of selection symbols, each selection symbol associated with a plurality of move specifications, each move specification corresponding to a rotation of the mechanical object through a number of stop positions, wherein the number of stop positions is different for at least two of the move specifications, and each move specification is associated with one of the selection symbols based on probabilities associated with said move specification;

at least one memory device which stores the move specifications and the probabilities associated with said move specifications;

a display device operable to displays the selection symbols to a player;

an input device which enables the player to select the selection symbols; and

at least one processor operable with the actuator, the memory device, the display device and the input device.

2. The gaming device of claim 1, wherein the rotatable mechanical object is movable to a position so that at least one of the award symbols is adjacent to the window.

3. The gaming device of claim 1, wherein at least one of the selection symbols includes a symbol which indicates direction.

4. The gaming device of claim 1, wherein each of the move specifications is associated with a different probability.

5. The gaming device of claim 1, wherein each of the award symbols include an award value.

6. The gaming device of claim 5, wherein at least one of the award values is a bonus value.

7. The gaming device of claim 1, wherein the rotatable mechanical object includes a reel.

8. The gaming device of claim 1, which includes at least one move indicator displayed on the display device after the player selects one of the selection symbols.

9. The gaming device of claim 1, which includes an award associated with each of the award symbols.

10. The gaming device of claim 9, which includes an input for accepting or rejecting at least one of the awards.

11. The gaming device of claim 1, which includes at least one primary game.

12. The gaming device of claim 11, wherein the primary game includes the selection symbols.

13. The gaming device of claim 11, which includes at least one bonus game, wherein the bonus game includes the selection symbols.

12

14. The gaming device of claim 1, which includes a plurality of light sources connected to the rotatable mechanical object, each of the light sources forming one of the award symbols.

15. The gaming device of claim 14, wherein each of the selection symbols includes a move indicator displayed on the display device.

16. A gaming device comprising:

a cabinet;

at least one actuator supported by the cabinet;

a rotatable mechanical object operatively coupled to the actuator, the rotatable mechanical object having a plurality of award symbols, each award symbol associated with a different stop position on the rotatable mechanical object;

a mask connected to the cabinet, the mask covering at least part of the rotatable mechanical object and defining at least one window which reveals one of a plurality of sets of the award symbols;

at least one award symbol indicator connected to the cabinet;

an award associated with each of the award symbols; at least one processor operable with the actuator and the display device, to:

enable a player to cause the rotatable mechanical object to move relative to the mask a number of stop positions according to one of a plurality of different move specifications, based on a plurality of different probabilities associated with the different move specifications, wherein the number of stop positions associated with a move specification is different for at least two of the move specifications.

17. The gaming device of claim 16, which includes an input device in communication with the processor which enables a player to accept the set or reject the set, causing the rotatable mechanical object to rotate to a stop position where the window reveals a different set to the player.

18. The gaming device of claim 16, which includes a game event associated with an initiation of rotation of the rotatable mechanical object.

19. The gaming device of claim 16, which includes an input device which enables a player to initiate rotation of the rotatable mechanical object.

20. The gaming device of claim 16, which includes a plurality of award symbol indicators, each of the award symbol indicators having a position adjacent to one of the award symbols in the revealed set.

21. The gaming device of claim 16, wherein the award symbol indicator includes at least one light source.

22. The gaming device of claim 16, wherein each of the award symbols in each of the sets is associated with a probability.

23. The gaming device of claim 16, wherein each of the award symbols include an award value.

24. The gaming device of claim 23, wherein at least one of the award values is a bonus value.

25. The gaming device of claim 16, wherein the rotatable mechanical object includes a reel.

26. A method for indicating an award to a player in a gaming device having a game operable upon a wager, said method comprising:

(a) providing a mechanical object rotatably connected to a cabinet of the gaming device;

13

- (b) providing a plurality of award symbols on the rotatable mechanical objects, each award symbol associated with a different position on the mechanical object;
- (c) providing a window adjacent to the mechanical object which reveals at least one of the award symbols to a player at a point in time;
- (d) displaying a plurality of selection symbols;
- (e) enabling a player to select at least one of the selection symbols, wherein different move specifications corresponding to a rotation of the mechanical object through a number of positions are associated with at least two different selection symbols based on probabilities associated with said move specifications;
- (f) rotating the mechanical object to a position based on which selection symbol the player selects; and
- (g) revealing at least one of the award symbols through the window.

14

- 5 27. The method of claim 26, which includes providing the player with an award associated with the revealed award symbol.
- 10 28. The method of claim 26, which includes providing the player with an award associated with the revealed award symbol and repeating steps (d) through (g) at least once.
- 15 29. The method of claim 26, which includes enabling the player to accept or reject an award associated with the revealed award symbol.
- 30. The method of claim 26, which includes enabling the player to accept or reject an award associated with the revealed award symbol and repeating steps (d) through (g) at least once if the player rejects the award associated with the revealed award symbol.
